Owen, Owen & Campion

UNITED STATES PATENT OFFICE.

CLARENCE F. WARNE, OF TOLEDO, OHIO.

TACKING-MACHINE.

1,310,590.

Specification of Letters Patent.

Patented July 22, 1919.

Application filed April 27, 1918. Serial No. 231,081.

To all whom it may concern:

Be it known that I, CLARENCE F. WARNE, a citizen of the United States, and a resident of Toledo, in the county of Lucas and State 5 of Ohio, have invented a certain new and useful Tacking-Machine; and I do hereby declare the following to be a full, clear, and exact description of the invention, such as will enable others skilled in the art to which 10 it appertains to make and use the same, reference being had to the accompanying drawings, and to the characters of reference marked thereon, which form a part of this specification.

15 My invention relates to machines for driving tacks and small nails. It has for its object a simple and efficient light weight machine that can be easily manipulated and controlled by the hand of the user. The 20 object of the invention is to provide a tack or small nail driving machine which may be readily shifted from one position to another to drive tacks or small nails wherever may be desired. It is particularly useful in 25 connection with upholstering work of all kinds, making of covers and in fact, may be used wherever sheet material such as fabric or metal or other material is to be secured by means of tacks or small nails.

30 The invention may be contained in many forms of construction. I have selected one form of construction for purposes of illustration and shall describe it hereinafter. The construction selected is illustrated in 35 the accompanying drawings:

Figure 1 is a side view of the construction selected, Fig. 2 is a longitudinal sectional view. Fig. 3 is an end view. Fig. 4 is an enlarged view of the lower end of the device. 40 Fig. 5 is a broken view showing the container for containing the tacks or nails. Fig. 6 is a detailed view of one of the springs used for guiding the tacks or nails to their proper position for driving. Fig. 7 45 illustrates the end of the chute for guiding the tacks or nails. Fig. 8 is a view of a lever used in shifting the tacks. Fig. 9 is a view of the dog operated by the lever shown in Fig. 8.

50 1 is the handle of the device. It is provided with a nipple 2 over which a hose may be placed to connect the device with a source of air supplied under pressure. In the handle 1 is located the central passage- 55 way 3 which communicates with the two passage-ways 4 and 5. A valve member 6 is

located in the handle 1 so as to control the passage-ways 4 and 5. The valve member 6 is provided with passage-ways 7 and 8 and also short channels 9 and 10. The valve 60 member 6 is held in its normal position by means of a spring 11 which is secured to the handle 1 and also to the valve member 6 to allow movement of the valve member 6 but so as to prevent rotation of the 65 valve member 6 within the handle 1. The spring 11 operates to cause the valve member 6 to return to its normal position when it has been pushed therefrom by the use of the finger. It is provided with a pin 12 which 70 limits the movement of the valve member 6 caused by the action of the spring 11.

When the valve member 6 is in its normal position, the passage-way 8 registers with the passage-way 5 and the passage-way 4 75 on one side of the valve member 6 is closed. The passage-way 4 on the other side of the valve member communicates with the exterior of the handle through the short channel 9 and the passage-way 7. When, however, the valve member 6 is pushed down, the passage-way 7 registers with the passage-way 4, and the passage-way 5 on one side of the valve member is closed while the passage-way 5 on the other side of the member 80 through the channel 10 and the passage-way 8, connects with the outside air.

The handle 1 is secured to a cylinder 13 by means of a suitable clamping bolt 14. It is so connected that the passage-way 4 90 communicates with the interior of the cylinder through a hole 15. The cylinder is also provided with an opening 16 that connects with the passage-way 5 through a tube 17. A piston 18 is located in the cylinder 13. It has a stem 19 that extends through a partition 20 that divides the cylinder into two parts. The opening 16 is so located as to permit the air under pressure to pass above the partition and below 100 the piston 18, while the opening 15 is located in the upper end of the cylinder and so as to permit the air to pass above the piston 18. The stem 19 is threaded and is connected to a hammer head 21 which is 105 located on the lower side of the partition 20. The hammer 21 is made in the form of a cone and is reciprocated in the lower end of the cylinder 13 by movements of the piston 18 caused by shifting of the valve 110 member 6 so as to permit the air under pressure to pass first to one side of the

piston 18 and escape from the other side and then pass to the other side and escape from the first side. Inasmuch as the valve member 6 by the action of the spring 11, 5 takes the normal position such that the lower side of the piston is connected with the source of air pressure supply, the piston 18 and the hammer 21 are normally held in their uppermost positions.

10 The upper end of the cylinder 13 is closed by an end plate 22. To the end plate 22 is secured a box or container 23 which is closed by a cover 24. The bottom of the box is provided with a slot 25 that extends 15 toward the center of the box. The tacks or small nails are placed in the box and by the shaking due to handling the instrument and the reciprocatory movements of the hammer, the nails or tacks are shaken so 20 that their points drop through the slot 25. At the end of the slot 25, the interior of the box communicates or connects with the chute 26 which has a slot 27 that forms a continuation of the slot 25. By the shaking 25 of the box in the use of the instrument, the tacks pass into the chute and fall down along the chute, the chute being of such size that the heads are held within the chute while the points extend through the slot 30 27, and are guided to the lower end of the cylinder 13 by the chute, where they are stopped by a forked spring member 28 which is secured to the chute. The chute is twisted 180° so that the points will extend downward 35 when the tacks or nails reach the bottom of the chute.

Around the lower edge of the cylinder 13 are located a plurality of conically arranged springs 29. The springs 29 may be 40 formed by cutting into one or more strips, sheet metal that extends 90° or 180° or entirely around the lower end of the cylinder in order that the proper amount of flexibility may be obtained. When the 45 spring members 29 are placed together, they form a cone having a nipple 30 through which the nails or tacks may be forced when they are driven by the hammer 21. One of the segments of the sheet metal is 50 provided with an opening 31 to permit the heads of the tacks or nails to pass and also a slot 32 which forms a continuation of the slot 27 located in the chute 26 and guides the points downward, the head being 55 retarded by the friction caused by the heads sliding along the cone surface of the segment of the sheet material until the tack or nail is supported in the upper end of the nipple 30 with the point of the nail or 60 tack located within the nipple 30 and extending toward the lower end of the nipple. This brings the nail or tack directly under the hammer 21 so that when the valve 6 is placed to connect the upper end of the 65 cylinder with the source of air pressure

supply the hammer will be driven down and the tack will be driven out of the elastic cone and into any article that may be desired. In this operation the elastic cone 33 will be forced open by the hammer 21 7 and upon the return movement of the piston 18, the valve member 6 being released, the elastic cone will again reform to its normal shape.

In order that the tacks may be dropped 7 one by one into the elastic cone 33 and guided to the nipple 30, the spring 28 operates to hold the tacks back by pressing on the top of the heads of the tacks. A dog 34 extends through the forked spring 28 8 and its lower end rides on the tops of the tacks. The dog 34 is operated by a lever 35 that is pivotally supported on a pin 36 that extends through a bracket 37. The bracket 37 is secured to the lower end of 8 the cylinder, also a bracket or brace 38 may be secured by the pin 36 and to the bracket 37. The brace 38 operates to hold the lower end of the chute 26 in position. The lever 35 is operated by a plunger 39. The plunger 9 extends through an opening in the lower end of the cylinder and is pressed against the cone 21 by means of the spring 40 that is secured to the cylinder such as by the screw 41. The lever 35 is connected to the plunger 39 by a pin and slot to allow swinging movements of the end of the lever 35 relative to the longitudinal movements of the plunger 39.

When the hammer 21 descends, the plunger 39 is forced outward which causes the dog 34 to engage the head of a tack or nail and push it past the restraining springs 28 and through the opening 31 and slot 32, and into the elastic cone 33. On the return of 1 the hammer 21, the tack or nail that is thus pushed into the cone slips down the slot 32 and underneath the end of the hammer and thus it drops into the nipple 30. Also the plunger 39 by the operation of the spring 1 40 moves inward and permits the dog 34 to engage the head of another nail or tack. Thus a succeeding tack is placed in position to be driven by a succeeding operation of the hammer 21.

The instrument may be provided with legs or guiding members 42 which may be adjustably secured to the cylinder 13 by clips 43 and screws 44. The members 42 operate to protect the elastic points of the cone 33.

The instrument may be provided with suitable backing material for sealing the air passageways and the piston 18 may be provided with suitable packing rings or other devices to obtain the full effect of the air pressure controlled by the valve member 6.

I claim:

1. In a tacking tool, a cone shaped hammer, a plunger operated by the surface of

- the hammer, a dog operated by the plunger, a chute for feeding the tacks to position of engagement by the dogs, a cage formed of elastic members for receiving the tacks from the chute, and means for guiding the tacks to beneath the hammer within the cage. 5
2. In a tacking tool, a cone shaped hammer, a plunger operated by the surface of the hammer, a dog operated by the plunger, 10 a chute for feeding the tacks to position of engagement by the dogs, and a cage formed of elastic members for receiving the tacks from the chute, the cage having a slot for guiding the tacks to beneath the hammer. 15
3. In a tacking tool, a cone shaped hammer, a plunger operated by the surface of the hammer, a dog operated by the plunger, a chute for feeding the tacks to position of engagement by the dogs, and a cage formed 20 of elastic members for receiving the tacks from the chute, the cage having a nipple and a slot for guiding the tacks within the cage from the chute to the nipple. 25
4. In a tacking tool, a handle for manipulating the tool having a Y passageway, a cylinder connected to the end of the handle and with the passageway of the handle, a reservoir for tacks mounted on one end of the cylinder, a chute connected to the reser- 30
- voir and extending to the lower end of the cylinder, a pneumatic hammer located in the cylinder, a means for directing tacks sequentially beneath the hammer and a valve member extending through the handle for controlling the passageways of the hammer. 35
5. In a tacking tool, a cylinder having a pneumatic hammer and passageways located above and below the piston of the hammer, a handle secured to the cylinder and extending substantially at right angles from the cylinder and having a branched passageway connected with the passageways of the cylinder, a spring pressed valve member extending through the handle and the branches of the passageway in the handle and a tack 40 reservoir secured to the top of the cylinder and a chute for conducting the tacks to beneath the hammer located in a transverse passageway extending through the branches of the branched passageway, the valve member operating to open the connection from the branched passageway to either of passageways of the cylinder and open the connection from the cylinder to the atmosphere through the transverse passageway. 45
- In testimony whereof I have hereunto signed my name to this specification. 50
- CLARENCE F. WARNEKE. 55
